UNITED STATES PATENT OFFICE.

WALTER F. BAILEY, OF LOS ANGELES, CALIFORNIA, ASSIGNOR TO JOHN H. JANSSEN,
OF LOS ANGELES, CALIFORNIA.

COMBINED PAN GREASER AND SCRAPER.

1,209,927.

Specification of Letters Patent. Patented Dec. 26, 1916.

Application filed October 18, 1915. Serial No. 56,625.

To all whom it may concern:

Be it known that I, WALTER F. BAILEY, a citizen of the United States, residing at Los Angeles, in the county of Los Angeles and 5 State of California, have invented new and useful Improvements in Combined Pan Greasers and Scrapers, of which the following is a specification.

My invention relates to a combined pan 10 greaser and scraper.

It is an object of this invention to construct a combined pan greaser and scraper which is extremely simple of construction, durable, and easy of manufacture.

It is another object to construct a device 15 of the kind described which is sanitary and which may be easily manipulated to insert a new pan-greasing member.

With these and other objects in view, 20 which will appear as the description proceeds, my invention consists in the construction and arrangement of parts hereinafter described and claimed.

In the accompanying drawings which 25 form a part of this specification, I illustrate a convenient and practical form of my invention, in which:

Figure 1 is a perspective view of my device. Fig. 2 is a top plan view of the front 30 part thereof. Fig. 3 is a section taken on line 3—3 of Fig. 2. Fig. 4 is a section taken on line 4—4 of Fig. 3.

The main body of my device consists of a handle 10 of sheet metal, which, at its forward end, is bent downwardly to form a curved portion and a scraper blade 11 which extends in a plane at right angles and transversely to the handle 10. In the fore part of the handle a pair of parallel clamp-engaging flanges or channels 12—12 are arranged. The same extend upwardly from the lateral edges of the handle and are made integral therewith. They consist of vertical members 13 and inwardly-turned strips 14. The 45 vertical members 13 are of less height in front, as at 15, and of greater height in the rear, as at 16, so that the upper edge thereof is slightly inclined toward the front. The handle is preferably provided with a lateral 50 flange 10' extending upwardly from the rear of the clamp-engaging flanges 12—12 with the portion of the flange adjacent to the rear of the flange members 12—12 inclined toward the horizontal, as at 17. The pitch of 55 the inclined portion 17 is the same as that

of the upper strips 14 of the flanges 12—12. Co-acting with said flanges is a clamp member 18. The same consists of a rectangular piece of sheet metal adapted to slidably engage the flanges 12—12. The front end of said clamp is provided with a downwardly extending flange 19 whose lower edge is serrated to form a series of teeth 20. The rear edge of the clamp is bent downwardly to form a flange 21 adapted to engage and slide 60 upon the inclined portion 17 of the flange 10' of the handle. Extending laterally from the rear edge of the clamp 18 is a pair of stop pins 22 which are formed integral with said clamp and extend beyond the flanges 65 12—12. A grease-spreading member 23, such as a pad of cotton-felt or the like, is held at the rear portion thereof in firm engagement between the clamp member 18 and the upper face of the body portion of the device so that the front end of said pad extends 70 substantially to the front end of the handle over the curved portion thereof to provide for a yielding action of the front end of the pad. In place of the cotton pad or the like, 75 a piece of bacon rind may be substituted.

From the foregoing description, the operation of the device will be easily understood. When it is desired to insert a fresh greasing-member, the clamp 18 is pushed 80 rearwardly, the flange 21 riding on the inclined portion 17 of the lateral flange 10' on the handle, until the clamp is entirely disengaged from the clamp-retaining flanges 12—12. A fresh pad of felt or the like is inserted between the clamp-retaining flanges 85 12—12 so that its rear end projects beyond the rear of the flanges and the clamp 18 is pressed downwardly thereon with the teeth 90 20 of the clamp engaging the same. The clamp 18 is now pushed forward between the clamp-retaining flanges. In view of the fact that the top strips of said flanges are inclined forwardly, the clamp will be wedged 95 in, securely holding the pad of felt in its position. The stop pins 22 will abut against the rear walls of the flanges and prevent any further forward movement of said clamp.

The pan is scraped by means of the scraper blade 11, and then, by turning the device 100 over, the pan may be greased by the pad of felt or the like, which is saturated with any suitable edible grease or fat.

It is thus seen that I have constructed an 105 extremely simple device whereby the greas-

ing member may be instantly removed and a new one inserted in its place. The device without the greasing member consists of but two parts and possesses no grooves or corners which are difficult to keep clean and sanitary.

It is obvious that changes in the construction and arrangement of my improved combined pan greaser and scraper may be made 10 by those skilled in the art without departing from the spirit of my invention as covered by the claims.

I claim:

1. In a device of the character as disclosed, 15 a handle, a blade, a pair of parallel clamp-engaging channels extending upwardly from said handle and spaced from said blade, the top members of said channels being inclined toward the front, a pair of flanges to the 20 rear of said channels, the upper edge of said flanges being inclined in the same direction as said top members, a fibrous pad removably mounted between said channels and extending in front thereof; a clamp member 25 slidably mounted in said channels, said clamp having pad-engaging teeth and a flange-engaging member, and means on said clamp to limit its forward movement.

2. In a device of the character as disclosed, 30 a handle, a blade, a pair of clamp-engaging members spaced from said blade, a fibrous pad removably mounted between

said members and extending therefrom, a clamp slidably mounted in said members, means on said clamp for engaging said pad, 35 and means for limiting the forward movement of said clamp.

3. In a device of the character disclosed, a handle bent downwardly at its forward end, a grease-spreading pad, means on said handle for detachably clamping the rear portion of said pad on the upper face of said handle so that the forward end thereof will extend substantially to the forward end of said handle and over the bent portion thereof to 45 provide for a yielding action of the forward end of the pad.

4. In a device of the character disclosed, a handle, a pair of clamp-engaging channels at the forward part of said handle, the top 50 members of said channels being inclined downwardly toward the forward end of the handle, a pad adapted to be placed between said channels so as to extend forwardly thereof, a clamp slidably mounted in said 55 channels adapted to engage and clamp said pad against the handle when said clamp is moved forwardly within said channels, and means to limit the forward movement of said clamp.

In testimony whereof I have signed my name to this specification.

WALTER F. BAILEY.
